[57] CLAIM

The ornamental design for a telephone handset, as shown and described.

DESCRIPTION

FIG. 1 is a perspective view of the telephone handset according to the present design illustrated with the antenna in a lowered position;

FIG. 2 is a top plan view thereof;

FIG. 3 is a left side elevational view thereof, the right side being symmetrical to the left side;

FIG. 4 is a front elevational view thereof;

FIG. 5 is a rear elevational view thereof;

FIG. 6 is a bottom view thereof; and

FIG. 7 is a fragmentary rear elevational view with the antenna in a raised position.

FIG. 1

FIG. 7

FIG. 2
